UNITED STATES PATENT OFFICE.

ROBERT F. METCALFE, OF ERIE, PENNSYLVANIA, ASSIGNOR TO SKINNER PATENT HOLDING COMPANY, OF ERIE, PENNSYLVANIA, A CORPORATION OF PENNSYLVANIA.

METHOD OF AND APPARATUS FOR CONTROLLING STEAM ENGINES.

Application filed December 4, 1919. Serial No. 342,321.

Where steam engines are used in certain relations, particularly in driving motor vehicles it is desirable, if not necessary with some designs to start the engine with a late 5 cut-off. It is also desirable after the engine is in operation to eliminate the throttle valve control and control the engine entirely by the cut-off so as to assure the greatest economy from the engine. It is in many instances desirable to be able to set the control 10 so as to automatically maintain a desired speed, the control permitting a change of this speed. In order to be effective such a controlling device must be rugged and yet 15 very sensitive. My invention relates to the problem generally just expressed as well as the details and features hereinafter described and claimed.

The invention is illustrated in the accompanying drawings as follows:

Fig. 1 shows an elevation, partly in section, of the engine control.

Fig. 2 a fragment of the controlling cam.

Fig. 3 an enlarged view of the bypass 25 valve.

Fig. 4 shows the valve gear in initial starting position.

Fig. 5 shows the valve gear in one of the later stages of control with the bypass valve 30 open.

1 marks the crank shaft of an engine, 2 and 3 opposed eccentrics, 4 and 5 straps on said eccentrics respectively, 6 and 7 rods connecting the eccentrics by means of pins 8 and 9 with a link 10. A sliding block 11 is arranged in the link and is connected by a pin 12 with a slide 13. The slide 13 is carried by a bearing 14 and connected with the valve rod 15.

40 It will be understood that the type of engine is not essential nor the type of valve. The invention is particularly useful, however, when utilized in connection with a uniflow engine because in such engines the fixed 45 compression requires a late cut-off to prevent stalling with a higher speed than is the case with counterflow engines.

A link 17 is pivotally secured by a pin 16 with the link 10 and connects the link 10 with a rock arm 19 by means of a pin 18. The rock arm 19 is fixed on a rock shaft 20, the rock shaft being carried by a bracket 29 on the frame. A rock arm 21 extends from the shaft 20 to a pin 23 on a block 24. The 55 arm 21 is provided with the slot 22 to per-

mit of the curved movement of the end of the frame with relation to the pin 23.

A push rod 25 extends from the block 24 and terminates in a ball 26, the ball being seated in a piston 27. The piston 27 is the 60 active element of a motor and operates in a cylinder 28. The cylinder 28 is carried by the bracket 29. A pipe 30 extends from the cylinder 28 and connects through a cross 31. A pipe 32 extends from the cross to a rotary 65 pump 33. The rotary pump is driven by a gear 34 (indicated in dash lines) which meshes with a gear 35 (also indicated in dash lines) mounted on the engine shaft 1. In consequence the pump has a speed varying 70 as the engine speed varies. A pipe 36 extends from a supply tank 37 to the pump. A pipe 38 extends from the cross 31 to a bypass valve 39. The bypass valve is provided with a valve disc 41. This valve disc has a 75 stem 41^a which extends into a guide plug 42. A spring 41^b tends to close the valve on its seat 41^c. The valve is provided with a minimum bypass opening 40. A push rod 43 extends upwardly from the valve 40 and a 80 projection 43^a is arranged on the valve disc 41 in the path of the rod 43. The rod 43 passes through a gland 45 in the valve 40 and a gland 44 on the body 81 of a throttle 85 valve 47. The throttle valve is provided with a stem 46 and operates on the seats 48 and 49. A spring 50 operates against a shoulder 50^a on the throttle valve stem and tends to hold the throttle valve in closed position. The stem 46 terminates in a fork 51 90 within which a cam roller 52 is mounted by means of a pin 53. The throttle valve is actuated by a controlling cam 54 which is mounted on a pin 57 carried by the bracket 29. The cam 54 has the controlling surfaces 95 54^a, 55 and 56 which operate upon the roller 52 to operate the throttle. The surface 54^a permits the throttle to close. From this the cam gradually increases in distance from the center at 56 so that with the cam 54 swung 100 toward the surface 56 the throttle is opened rather abruptly and the continued movement of the cam does not change the steam admission but actuates the rod 43 so as to vary the position of the bypass valve disc 41.

I utilize the same cam 54 for actuating the cut-off mechanism. A spring 59 is anchored by means of a stud 58 on the cam 54 and extends to a pin 60 arranged on a rock arm 63. The rock arm is fixed on a shaft 64. A roller 105

60^a is carried by the pin 60 and with the cam 54 in neutral position the roller 60^a is located in a socket 60^b, the sides of this socket making a quick-acting cam for swinging the 5 rock arm 63 with the swinging movement of the cam 54. The surfaces 61 and 62 at each side of the socket 60^b are arcs of a circle about the center of the shaft 57 and consequently simply provide a rolling surface for 10 the roller 60^a and consequently lock the rock levers 63 in a given position after the cams at the sides of the socket 60^b have moved it. The spring 59 holds the rock lever 63 in a position following the surfaces 61 and 62 and 15 compels a movement of the rock lever following the cams at the sides of the socket 60^b so that the rock lever will drop into the socket when the cam 54 is brought to neutral. A rock arm 65 is mounted on the shaft 64 20 and connected by a bracket 67 with a cylinder 68. A plunger 69 is mounted in the cylinder 68. A spring 70 operates against one head of the cylinder and against the plunger 69, the piston being provided with a 25 spring seat 72. The rod 75 is screw-threaded and extends into a screw-threaded opening 73 in the piston and is locked by a jam nut 74. A shoulder 76 limits the movement of the piston in the cylinder 68. A controlling 30 lever 78 is fixed with the cam 54 and provided with a handle 77. This lever operates over a segment 79. As shown the segment is scaled and the lever has an indicating point 80. The neutral point on the segment is indicated at N. The point A indicates a movement of the cam to swing the rock lever 63 out of the notch 60^b. M indicates the maximum forward position of the controlling lever. Moving the controlling lever to R 40 moves the cam surface 55 into position on the roller 52 and also throws the rock lever 63 in a reverse direction so as to throw the cut-off. For reverse control the throttle is actuated rather than the cut-off and this is 45 accomplished through the cam surface 55 which is so graduated as to give a ready control of the throttle.

Steam is supplied to the throttle valve from a source of supply through the pipe 50 82 and is delivered to the engine through a pipe 83.

The operation of the device is as follows: When the operating lever 77 is thrown to the position A (see Fig. 4) the rock lever 55 63 is rocked. This rocking of the lever 63 acting through the rock arm 65 moves the cylinder 68 toward the right. At this moment the engine is, of course, stationary and any liquid there may be in the cylinder 28 60 is forced through the pipe 30 by way of the opening 40 in the bypass valve and by way of the pipe 38^a, pipe 85 to the discharge 84 leading to the tank 37. Consequently the movement of the cylinder 68 is accompanied 65 by an approximately equal movement, either immediate or immediately following, of the rod 75 and with it the rock arms 21 and 19 and the link 10 is thus depressed throwing the link to a late cut-off ahead. With the parts at this position the cam at the beginning of the surface 56 reaches the roller 52 and begins to open the throttle. As the throttle is opened and the engine started the pump 33 is started and begins to force liquid through the pipes 32 into the cylinder 28. At the same time some liquid is forced through the bypass opening 40. As the engine speeds up the resistance to the flow of liquid through the metered opening 40 increases and this resistance as it gradually builds up results in pressure on the liquid which pressure is communicated to the piston 27, thus moving the piston 27 toward the left against the resistance of the spring 70. This movement toward the left of the piston 27 is accompanied by a movement of the rock arms 21 and 19 and consequently of the link 10 so as to gradually shorten the cut-off.

Inasmuch as the resistance to the flow of liquid varies very greatly with its velocity through a restriction, such as the metered opening 40, the cut-off is very quickly brought to a position which will give an engine speed which may for convenience be designated a "minimum pre-determined speed". The throttle in the meantime is completely open so that a further movement of the throttle has no effect in increasing or decreasing the flow of steam. The continued movement, however, of the throttle through the action of the cam 56 acts through the rod 43 upon the disc 41 and opens the bypass valve, thus increasing the area of restriction at this bypass and consequently decreasing the resistance to the flow of liquid. With this decrease in resistance there is a consequent decrease in pressure which results in a preponderance of force by the spring 70 so as to effect a movement of the rod 75 toward the right and with it through the linkage 105 hereinbefore described to the link 10 so as to increase the cut-off. It will be seen, therefore, that by setting the bypass valve at any position the resistance through the restriction is so measured with relation to the speed 110 as to effect a very close response in the speed of the engine. This is due to the fact that any change in velocity through this restriction varies the resistance as the square of the velocity. Consequently a very slight 115 change in the velocity, this change being brought about by a change in the speed of the engine, makes such a variation in the resistance and consequently in the pressure of the liquid as to vary the cut-off to a point 120 which will maintain the engine approximately at the desired speed.

In the normal running of the engine it is desirable to compel the operator to control the speed by the cut-off and this mechanism 125 130

accomplishes this purpose but with the reverse this is not necessary. To reverse the engine, therefore, the cam 54 is swung as the lever 78 is moved downwardly so as to

5 swing the rock lever 63 and with it the rock lever 65 to carry the rod 75 to the left. This carries the link 10 immediately to reverse position and the control of the engine is thus effected by a throttling action on the cam 55, 10 the cam 55 being shaped to effect this result.

Should the engine be driven by the vehicle as in coasting down grade the bypass valve will not entirely relieve the pump and I, therefore, provide a relief valve 87. This 15 is connected with the connection 31 by a pipe 86 and with the overflow 85 by a pipe 31^a. It is provided with a valve disc 88 from which extends a stem 89. A spring 90 operates against the stem and the force 20 of the spring may be adjusted by the screw 91. The screw 91 is carried by the frame 92 extending from the valve. In this way the valve may be loaded to any pressure desired.

What I claim as new is:—

25 1. The method of controlling steam engines which consists in initially directly controlling the cut-off, then controlling the cut-off through a motor actuated by pressure responsive to the speed of the engine, and varying the pressure incident to a given speed 30 of the engine to adjust the speed of the engine through the cut-off.

2. The method of controlling steam engines, which consists in manually initially 35 throwing a variable cut-off to late cut-off; driving a liquid at a speed varying with the speed of the engine; regulating the cut-off with the liquid pressure; and bypassing and restricting the liquid to control its pressure.

40 3. The method of controlling steam engines, which consists in manually initially throwing a variable cut-off to late cut-off; driving a liquid at a speed varying with the speed of the engine; regulating the cut-off with the liquid pressure; bypass and restricting the liquid to control its pressure; and varying the amount of restriction to vary the regulation.

45 4. The method of controlling steam engines, which consists in manually throwing a variable cut-off valve gear to late cut-off as the engine throttle is opened; driving a liquid at a speed varying as the speed of the engine varies; regulating the cut-off of the engine with the liquid pressure; and bypassing and restricting the liquid to control the pressure.

50 5. The method of controlling steam engines, which consists in manually throwing a variable cut-off valve gear to late cut-off as the engine throttle is opened; driving a liquid at a speed varying as the speed of the engine varies; regulating the cut-off of the engine with the liquid pressure; bypassing 55 and restricting the liquid to control the

pressure; and varying the amount of restriction to vary the regulation.

6. The method of controlling steam engines which consists in initially directly controlling the cut-off, then controlling the 70 cut-off through a motor actuated by pressure responsive to the speed of the engine, driving a confined liquid at a speed varying as the speed of the engine, regulating the cut-off of the engine with the liquid pressure, bypassing and restricting the liquid to control its pressure, and varying the restriction to vary the regulation.

7. In a steam engine control, the combination of a variable cut-off valve gear; a liquid pump driven by the engine; a manually actuated controlling device; a yielding connection between the valve gear and the device; a motor actuated by the liquid pumped; and means for communicating the movement of the motor to the valve gear against the resistance of the connection.

8. In a steam engine control, the combination of a variable cut-off valve gear; a liquid pump driven by the engine; a manually actuated controlling device; a yielding connection between the valve gear and the device; a motor actuated by the liquid pumped; and means for communicating the movement of the motor to the valve gear against the 105 resistance of the connection whereby the device may throw the valve to late cut-off and the motor reduce the cut-off as the speed increases.

9. In a steam engine control, the combination of a variable cut-off valve gear; a throttle; a manually actuated controlling device actuating the throttle; a yielding connection between the device and the valve gear, the device and connection operating to initially 100 open the throttle and to set the valve gear at late cut-off; a motor acting against the resistance of said connection to actuate the valve gear; and a liquid pump driven by the engine and actuating the motor, said pump 110 varying the pressure with the speed of the engine.

10. In a steam engine control, the combination of a variable cut-off valve gear; a throttle; a manually actuated controlling device actuating the throttle; a yielding connection between the device and the valve gear, the device and connection operating to initially open the throttle and to set the valve gear at late cut-off; a motor acting against 115 the resistance of said connection to actuate the valve gear; a liquid pump driven by the engine and actuating the motor; and a restricted bypass for the liquid pumped.

11. In a steam engine control, the combination of a variable cut-off valve gear; a throttle; a manually actuated controlling device actuating the throttle; a yielding connection between the device and the valve gear, the devices and connection operating 125 130

to initially open the throttle and to set the valve gear at late cut-off; a motor acting against the resistance of said connection to actuate the valve gear; a liquid pump, driven by the engine and actuating the motor; a restricted bypass for the liquid pumped; and means for varying the restriction of the bypass as the throttle is opened.

12. In a steam engine control, the combination of a variable cut-off valve gear; a throttle; a manually actuated controlling device actuating the throttle; a yielding connection between the device and the valve gear, the devices and connection operating to initially open the throttle and to set the valve gear at late cut-off; a motor acting against the resistance of said connection to actuate the valve gear; a liquid pump driven by the engine and actuating the motor; a restricted bypass for the liquid pumped; and means for varying the restriction as said device is actuated after the opening of the throttle.

13. In a steam engine control, the combination of a variable cut-off valve gear; a throttle; a controlling cam having a cam surface for actuating the throttle and a cam

surface for actuating the valve gear; a yielding connection between the cam and valve gear, the devices and connection operating to initially open the throttle and to set the valve gear at late cut-off; a liquid actuated motor operating against said resistance; and a pump actuated by the engine and delivering liquid under pressure to said motor.

14. In a steam engine control, the combination of a variable cut-off valve gear; a throttle; a controlling cam having a cam surface for actuating the throttle and a cam surface for actuating the valve gear; a yielding connection between the cam and valve gear, the devices and connection operating to initially open the throttle and to set the valve gear at late cut-off; a liquid actuated motor operating against said resistance; a pump actuated by the engine and delivering liquid under pressure to said motor; a bypass restriction; a valve in said restriction; and a device carried with the throttle for actuating said valve.

In testimony whereof I have hereunto set my hand.

ROBERT F. METCALFE.
